SHOE FORM

Alfred G. Legge, Brockton, Mass.

Application August 1, 1934, Serial No. 737,939

4 Claims. (Cl. 12—128.2)

This invention relates to shoe forms adapted to be placed in shoes to maintain them in their proper shape for display purposes or when not being worn. More particularly, the invention is directed to that type of shoe form which includes two complementary laterally movable parts which are separated and held resiliently in engagement with the shoe upper.

It is an object of the present invention to provide an improved form of this general type.

The invention will be more clearly understood from the following description in conjunction with the accompanying drawings: in which,

Fig. 1 is a plan view of a form embodying the invention;

Fig. 2 is a longitudinal sectional elevational view of a shoe in which is positioned the form shown in Fig. 1;

Fig. 3 is a sectional view taken upon the line 3—3 of Fig. 1;

Fig. 4 is a plan view of a modified construction of form embodying the invention, partly broken away;

Fig. 5 is a sectional view taken upon the line 5—5 of Fig. 4;

Fig. 6 is a plan view of a modified construction of form embodying the invention;

Fig. 7 is a plan view of the form shown in Fig. 6 with the parts in different position;

Fig. 8 is a longitudinal sectional elevational view of a shoe in which is positioned the form shown in Figs. 6 and 7; and

Fig. 9 is a sectional view taken upon the line 9—9 of Fig. 6.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

The form shown in Figs. 1 to 3 inclusive comprises a toe part 10 which is split longitudinally to provide two complementary portions 11 and 12. The portion 12 is provided with cavities 13 and 14 which communicate with holes 15 and 16 extending from the central face 18. Screws 19 and 20 are fixed in the portion 11 and extend through the holes 15 and 16 respectively so that their heads 21 and 22 are positioned respective-

ly in the cavities 13 and 14 and are adapted to engage the bottoms 23 and 24 of the cavities to limit the lateral movement of the portions 11 and 12 away from one another. The portions 11 and 12 normally are urged outward away from one another by a bowed spring 25 the ends of which are provided with elongated slots 26 and 27 adapted to receive the screws 19 and 20 respectively. A heel part 30 is provided at one end with a block 31 adapted to engage the heel part 32 of the upper of the shoe 33. The other end of the heel part 30 extends between the rear end of the spring 25 and the central face 35 of the portion 11 of the toe part and is pivotally mounted upon the screw 20. It will also be noted that the heel part 30 can be moved to a position as indicated in the dotted lines in Fig. 1 to conform to the general longitudinal shape of the shoe.

In the construction shown in Figs. 4 and 5, the toe part 10' likewise is formed with two complementary portions 11' and 12' which are held together by the screws 19' and 20' so as to permit limited lateral movement. It will be noted, however, that the bottom of the cavity 13' is positioned a greater distance from the central face 18' than is the bottom of the cavity 14'. The heel part 30' extends between the central faces 18' and 35' and is pivotally mounted upon the screw 20. Springs 40 and 41 are suitably secured upon opposite sides of the heel part 30' so as to extend therefrom forwardly and outwardly to engage respectively the central faces 35' and 18'. The springs 40 and 41 tend to urge the portions 11' and 12' outwardly away from one another and at the same time tend to pivot the same about the screw 19' to force the forward ends inwardly. However, when the toe part 10' is positioned in a shoe so that the toe portion of the shoe upper exerts an inwardly directed pressure upon the rear ends of the portions 11' and 12' against the action of the springs 40 and 41, there is a tendency for the forward ends of the portions 11' and 12' to be moved outwardly about the screw 19' to exert a resilient pressure against the shoe upper.

In the modified construction shown in Figs. 6 to 9 inclusive the toe part 10'' likewise is formed with two relatively movable complementary portions 11'' and 12''. The forward ends 50 of the portions 11'' and 12'' are held together for limited lateral movement by the screw 19'' engaging the portion 11'' and with its head 21'' movable in the cavity 13'' and adapted to engage the bottom 23'' thereof. Horizontal longi- 55

tudinally extending slots 45 and 46 are provided in the portions 11" and 12" extending from the rear ends thereof forwardly and with their bottoms 47 and 48 inclined inwardly. A wire spring member 50 of substantially triangular shape extends between the portions 11" and 12" and into the slots 45 and 46 so as to engage the bottoms 47 and 48 of the slots. Pins 51 and 52 extending across the slots 45 and 46 prevent displacement of the spring member 50. The forward end of the heel part 30" extends between the faces 18" and 35" and is pivotally mounted upon the spring member 50.

As the toe part 10" is inserted into a shoe, the heel part 30" is urged forwardly causing the spring member 50 to move forwardly relative to the portions 11" and 12" and exert a cam action thereon tending to move them outwardly relative to one another and hold them resiliently in engagement with opposite sides of the toe portion of the shoe upper. The action and function of this form is otherwise similar to that illustrated in Figs. 4 and 5.

I claim:

1. A shoe form having a longitudinally split toe part, guide means connecting said portions of the toe part near the forward end thereof permitting limited relative lateral movement, said portions of the toe part each having a slot

with a surface which extends forwardly and inwardly, a resilient member extending into said slots and longitudinally movable therein, and a heel part connected to said member.

2. A shoe form having a longitudinally split toe part, a pair of guides connecting said portions of the toe part permitting limited relative lateral movement, and a bowed leaf spring held between said portions by said guides and tending to move said portions away from one another.

3. A shoe form having a longitudinally split toe part, guides connecting said portions of the toe part permitting limited relative lateral movement, resilient means interposed between said portions tending to move them away from one another, and a heel part connected to one of said guides and movable laterally relative thereto, said resilient means being arranged to exert a resilient pressure upon said heel part.

4. A shoe form having a longitudinally split toe part, a resilient member and a guide member connecting said portions of the toe part permitting limited relative lateral movement thereof, and a heel part connected to one of said members and movable laterally relative thereto, said resilient member being arranged to exert a resilient pressure upon said heel part.

ALFRED G. LEGGE.
